ENERGIZING OR TENSIONING DEVICE FOR SPIRAL SPRINGS.

1,292,267.

Specification of Letters Patent. Patented Jan. 21, 1919.

Application filed April 14, 1915. Serial No. 21,422.

To all whom it may concern:

Be it known that we, Sir ARTHUR TREVOR DAWSON, knight, and GEORGE THOMAS BUCKHAM, both subjects of the King of Great Britain, residing at Vickers House, Broadway, Westminster, in the county of London, England, have invented certain new and useful Improvements in Energizing or Tensioning Devices for Spiral Springs, of which the following is a specification.

This invention relates to an improved method of and means for adjusting the tension of spiral springs of the kind that are used in connection with the crank shafts of automatic guns, this adjustment of the tension being herein referred to as the energizing or tensioning of the springs. These springs are usually mounted in spring cases composed of two parts, one fixed to the adjacent recoil plate and the other connected to, and therefore movable angularly with, the crank shaft, one end of the spring being connected to the fixed part and the other to the angularly movable part of the spring case. Such arrangements as at present employed are disadvantageous owing to the fact that the energizing or tensioning of the spring necessitates two men being employed and leads to a considerable expenditure of time. The chief object of the present invention is to provide an arrangement or device whereby the energizing or tensioning of the spring can be quickly and satisfactorily effected by one person.

According to this invention the spring is energized or tensioned by temporarily connecting the two parts of the case together after a certain amount of tension has been placed on the spring by the rotation of the movable part of the spring case, then disengaging the fixed part of the case from the recoil plate and angularly moving the two parts together with the crank in the proper direction and finally causing the fixed part to reengage with the recoil plate in a different relative angular position. By repeating this operation the requisite number of times the spring can be tensioned to the desired extent. For the purpose of the invention the aforesaid angularly movable part of the spring case may be slidably connected by a number of keys or otherwise to the crank shaft, and the fixed part may be similarly connected to the recoil plate, the length of

the keys appertaining to the fixed part being 55 smaller than that of the keys appertaining to the angularly movable part so that by sliding the two parts outwardly the fixed part can be disengaged from the recoil plate without disengaging the angularly movable 60 part from the crank shaft.

In order that the said invention may be clearly understood and readily carried into effect, we will describe the same more fully with reference to the accompanying drawings, in which:—

Figures 1 and 2 are respectively a sectional rear elevation and a side elevation showing one constructional form of the invention as applied to an automatic gun. 70

Figs. 3 and 4 are views similar to Figs. 1 and 2 showing another constructional form of the invention also as applied to an automatic gun.

In these figures, A is the crank shaft and 75 B is part of the recoil plate which is fixed so far as angular movement is concerned. C is the spiral spring. D is the angularly movable part of the spring casing and E is the fixed part of this casing. 80

In the example shown by Figs. 1 and 2 the outer end of the crank shaft is provided with three keys *a, a, a*, set at an angle of 120 degrees apart around the periphery of the crank. These keys engage with corresponding keyways in a hub or sleeve A' which has a hexagonal outer surface to receive the angularly movable part D of the spring case which is prevented from moving axially for example by a grub-screw or a screw-threaded stud *d'* passing through the boss D' of the part D and engaging with the hub or sleeve A'. One end of the spiral spring C is attached to the hub or sleeve A' and the other end is attached to the part E of the 95 spring case; this part is connected to a fixed boss B' on the recoil plate B by keys and keyways *b, b, b*, also arranged at an angle of 120 degrees apart, the length of these keys being, as aforesaid, less than that 100 of the keys *a, a, a*.

To energize or tension the spring, the crank shaft A is rotated in the direction of the arrow in Fig. 2 against the resistance of the spring C to move the lock to the breech 105 open position, and through an angle sufficient to bring holes *d, d, d* in the angularly movable part D of the spring case opposite

corresponding holes *e*, *e*, *e* in the other part E of the spring case (say 120 degrees). This rotation is effected by means of the crank handle which is not shown but is situated at 5 the end of the crank shaft farthest from the spring case as is well understood. A tommy bar is then inserted into the aforesaid coinciding holes, thus preventing relative angular movement between the two parts D, E 10 from taking place. The aforesaid grub screw *d'* is then removed and the two parts of the spring case shifted axially outward until the keys *b*, *b*, *b* appertaining to the fixed part E are clear of their keyways, the 15 keys *a*, *a*, *a* meanwhile remaining in engagement with their keyways. The crank shaft is then rotated through an angle of 120 degrees in the reverse direction to that indicated above. The parts of the spring case 20 are then pushed back into place to cause the keys *b*, *b*, *b* to reengage with their corresponding keyways and the tommy bar is withdrawn. The crank shaft and the part D are then in their original position but the 25 point of attachment of the spring C to the part E has assumed the new position indicated at X in Fig. 2. The tension on the spring has thus been increased permanently by the amount of tension imparted thereto 30 by the aforesaid movement of the part D in the direction of the arrow. The above described operation is repeated if necessary until the spring has received the required degree of tension.

35 In the construction illustrated by Figs. 3 and 4 the crank shaft A is directly attached to the boss D' of the angularly movable part D of the spring case by means of three keys *a*, *a*, *a* arranged as aforesaid at an angle of 40 120 degrees apart, and this part of the spring case is prevented from sliding off the keys by a spring pin or split pin *d'* passing through the boss D' and the crank shaft A. The fixed part E of the spring case is attached to the boss B' of the adjacent recoil plate B by two sets of keys *b*, *b*, *b* and *b'*, *b'*, each set being three in number. These 45 keys are arranged in two rows on the boss at a suitable distance apart axially and are so placed as regards their angular position that each key of one set lies opposite a gap existing between two keys of the other set. Corresponding keyways are provided in the fixed part E of the spring case. This arrangement of keys and keyways thus constitutes a species of bayonet joint connection 50 and prevents the spring case from being accidentally fully withdrawn from the crank shaft when said case is displaced axially to 55 free the fixed part E of the case from the adjacent recoil plate B, owing to the fact that the length of the keys *b*, *b*, *b* and *b'*, *b'*, is less than that of the keys *a*. The operation 60 of this construction is substantially the same as that hereinbefore described.

It is to be understood that our improvements can be employed in conjunction with spiral springs operating upon oscillating shafts other than the crank shafts of automatic guns.

70

What we claim and desire to secure by Letters Patent of the United States is:—

1. A method of energizing or tensioning a spiral spring which is connected at one end to a member normally attached to a 75 fixed part and at the other end to a member attached to an oscillating shaft, consisting in angularly displacing said shaft to place a certain amount of tension on the spring, connecting the two members together, disengaging the first mentioned member from the fixed part to which it is normally attached, angularly moving the two members, together with the shaft, in the reverse direction to the initial movement given to the 80 shaft and finally re-connecting said first mentioned member to its fixed part in a different relative angular position.

80

2. A method of energizing or tensioning a machine gun spiral spring which is connected at one end to a member normally attached to the recoil plate of the gun and at its other end to a member attached to the oscillating crank shaft of the gun, consisting in angularly displacing said 90 crank shaft to place a certain amount of tension on the spring, connecting the two members together, disengaging the first mentioned member from the recoil plate to which it is normally attached, angularly moving the two members, together with the crank shaft, in the reverse direction to the initial movement given to the crank shaft and finally re-connecting said first mentioned member to the recoil plate in a different angular position.

90

3. In an apparatus for energizing or tensioning a spiral spring, the combination with an oscillating shaft, a member connected to one end of the spring, and a second member to which the other end of the spring is connected, of means for slidably connecting the first mentioned member to said shaft, a fixed part and means for detachably connecting said second member in different angular positions to said fixed part.

105

4. In an apparatus for energizing or tensioning a spiral spring, the combination with an oscillating shaft, a member connected to one end of the spring, and a second member to which the other end of the spring is connected, of means for slidably connecting the first mentioned member to said shaft, a fixed part, and a key and keyway connection between said second member and said fixed part.

115

5. In an apparatus for energizing or tensioning a spiral spring, the combination with an oscillating shaft, a member con-

120

130

nected to one end of the spring, and a second member to which the other end of the spring is connected, of a key and keyway connection between the first mentioned member and the shaft, and a key and keyway connection between said second member and said fixed part.

6. In an apparatus for energizing or tensioning a spiral spring, the combination 10 with an oscillating shaft, a member connected to one end of the spring, and a second member to which the other end of the spring is connected, of a sleeve, means for connecting the first mentioned member to the sleeve, means for slidably connecting said sleeve to the shaft, a fixed part and a key and keyway connection between said second member and said fixed part.

7. In an apparatus for energizing or tensioning a spiral spring, the combination 20 with an oscillating shaft, a member connected to one end of the spring, and a second member to which the other end of the spring is connected, of a key and keyway connection between the first mentioned 25 member and the shaft and staggered keys for connecting said second member to said fixed part.

In testimony whereof we affix our signatures in presence of two witnesses.

ARTHUR TREVOR DAWSON.
GEORGE THOMAS BUCKHAM.
